Primary Examiner — Cynthia R Underwood

(57) **CLAIM**

I claim the ornamental design for a tablet keyboard case, as shown and described.

DESCRIPTION

FIG. 1 is a front elevational view of a tablet keyboard case showing my new design;
 FIG. 2 is a rear elevational view thereof;
 FIG. 3 is a left side elevational view thereof;
 FIG. 4 is a right side elevational view thereof;
 FIG. 5 is a top plan view thereof;
 FIG. 6 is a bottom plan view thereof;
 FIG. 7 is a front, left, bottom perspective view thereof; and,
 FIG. 8 is a rear, right, top perspective view thereof.

1 Claim, 8 Drawing Sheets---
